UNITED STATES PATENT OFFICE.

ADOLPH WERNER AND WILLIAM H. FETTER, OF TURTLE CREEK, PENNSYLVANIA.

COLLAR-BUTTONING DEVICE.

1,063,092.

Specification of Letters Patent.

Patented May 27, 1913.

Application filed November 24, 1911, Serial No. 662,139. Renewed March 29, 1913. Serial No. 757,692.

To all whom it may concern:

Be it known that we, ADOLPH WERNER and WILLIAM H. FETTER, citizens of the United States of America, residing at Turtle Creek, 5 in the county of Allegheny and State of Pennsylvania, have invented certain new and useful Improvements in Collar-Buttoning Devices, of which the following is a specification, reference being had therein to 10 the accompanying drawing.

This invention relates to a collar buttoning device, and the primary object of our invention is to facilitate the wear of a collar in opening stiffly-starched button holes and 15 placing the button hole ends of a collar upon a collar button.

Another object of this invention is to provide a buttoning device that is simple in construction, durable and highly efficient for 20 the purposes for which it is intended.

A further object of our invention is to provide a buttoning device that can be swung at any desired angle relatively to the collar button thereby facilitating the placing 25 of the button hole end of a collar upon a collar button.

We attain the above objects by a mechanical construction that will be hereinafter specifically described and then claimed, and reference will now be had to the drawing, 30 wherein:—

Figure 1 is a perspective view of the device as applied to a collar button, Fig. 2 is an enlarged elevation of the device as applied to a button. Fig. 3 is a similar view of a detached device. Fig. 4 is an end of the same, and Fig. 5 is an enlarged cross sectional view of the device taken on the line *v—v* of Fig. 5.

40 A device in accordance with this invention is made of a single piece of material, as German silver or other metal, the device being made from a blank that tapers from one end thereof to the opposite end. The 45 blank is rolled to form a hollow tapering body 1 resembling a pin. The material at the small end of the body is bent or reamed to provide a closed rounded end 2, and the material at the opposite end of the body is

cut away upon diametrically opposed sides 50 to provide slots 3. These slots are adapted to add resiliency to the large end of the body and facilitate the springing of the large end of the body over the head 4 of a collar button 5. In providing the slots 3, the large 55 end of the device has two diametrically opposed arms 6 and the outer ends of these arms are bent inwardly, as at 7 upon a curve that will conform to the periphery of the collar button head 4.

To limit the movement of the large end of the body upon the head 4, the large end of the body is provided with two inwardly projecting oppositely disposed teats 11 and 12. The teats 11 and 12 are located at the inner 60 ends of the slots 3, the teat 11 forming part of one of the arms 6, and the teat 12 a part of the other arm 6. These teats engage the periphery of the collar button head 4 and limit the movement of the device upon the 65 button head to that extent that the arms 6 snugly embrace the head and guide the button hole ends 13 of a collar 14 on to the button. The teats are formed by depressing the material of the arms.

We attach considerable importance to the manner of slotting the large end of the body, as the device can be freely moved in all directions upon the button head, when the slots 3 are maintained in the direction of 70 movement. When the slots 3 are opposite the direction of movement, the inwardly bent end 7 will engage upon the shank of the collar button and the device will be pried from the collar button.

75 What we claim is:—

A collar buttoning device comprising a tapering body circular in cross section at any point throughout its length and slotted to provide a pair of oppositely disposed 80 arms, the slit in the body extending from the enlarged end to a point in proximity to the smaller end thereof, each of said arms having its free end curving inwardly to engage a major portion of the head of a collar 85 button, said tapering body gradually increasing in diameter from its smaller end to the inturned portions of said arms, each of

said arms having its free end provided with a ⁵teat such teats being oppositely disposed for limiting the movement of the enlarged end of the body upon the head of the button, the smaller end closed and rounded to prevent injury to the collar and constituting the entering end.

In testimony whereof we affix our signatures in the presence of two witnesses.

ADOLPH WERNER.

WILLIAM H. FETTER.
